UNITED STATES PATENT OFFICE.

SIDNEY MITCHELL, OF NEW YORK, N. Y.

PULP-BEATER.

1,277,630.

Specification of Letters Patent. Patented Sept. 3, 1918.

Application filed February 7, 1918. Serial No. 215,771.

To all whom it may concern:

Be it known that I, SIDNEY MITCHELL, a citizen of the United States, residing at New York, in the county of New York and State of New York, have invented certain new and useful Improvements in Pulp-Beaters; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

The present invention relates, generally, to improvements in pulp beating machines commonly employed in the paper manufacturing industry; and the invention has reference, more particularly, to an improved construction of beater or breaker adapted to beat and tease out the fibers of the raw material to produce a proper pulp requisite to the carrying on of paper manufacture.

The invention has for its principal object to provide a means in connection with the beater mechanism for separating and discharging such portions of the raw material as has been properly beaten out or pulped, while still retaining that portion of the same, subject to the further action of the beater mechanism, which requires further treatment to reduce the same to the proper beaten or pulped condition, thus rendering the operation of the machine more or less continuous in its discharge of pulp, and eliminating the necessity of working over and over that portion of the raw material which has been properly reduced while awaiting the reduction of the more resistant portions of the same, thereby saving both time and energy.

The invention has for a further object to provide a novel arrangement of means for automatically separating reduced pulp from unreduced pulp, so related to the beater mechanism that the reduced pulp is discharged from the beater while the unreduced pulp is returned to the same, such separating arrangement being of a character which is positively free from any liability to clogging or obstruction.

Other objects of the present invention, not at this time more particularly enumerated, will be clearly understood from the following detailed description of the same.

The invention consists, primarily, in the

novel construction of beater or breaker hereinafter set forth; and the invention consists, furthermore, in the novel arrangements and combinations of the various devices and parts, as well as in the details of the construction of the said parts, all of which will be hereinafter more fully described, and then finally defined in the appended claims.

The invention is clearly illustrated in the accompanying drawings, in which:

Figure 1 is a plan view of a beater mechanism made according to and embodying the principles of my present invention, a portion of the hood inclosing the beater roll being broken away.

Fig. 2 is a vertical longitudinal section of the same, taken on line 2—2 in said Fig. 1.

Fig. 3 is a detail vertical longitudinal section of the water-screen box forming a portion of the pulp separating devices.

Similar characters of references are employed in all of the hereinabove described views, to indicate corresponding parts.

Referring now to the said drawings, the reference character 1 indicates the usual beater tub in which the beater mechanism and the novel separating devices are mounted, and in which the raw material to be pulped and the water for softening the same, and assisting its circulation around the tub to the beater roll, is received. Arranged within the tub is the usual mid-feather 2 which terminates short of each end of the tub, and which serves to properly divide the tub to provide the desired continuous circulatory passage therein. Mounted between one side wall of said tub and said mid-feather 2 is the usual beater roll 3, having the series of radially projecting fly-bars 4 on its circumference. A transversely journaled driving shaft 5 is mounted in connection with said tub upon which the roll 3 is fixed, said shaft being provided with a suitable belt pulley 6, or other suitable means for driving the same. Arranged beneath said beater roll 3 is any desired form of base-plate 7, with which the beater roll co-operates in beating out the raw material into the required pulp. Extending over the exposed upper portion of the beater roll 3 is an inclosing hood 8, having a portion substantially concentric to the circumference of the beater roll 3 in which is provided a transverse discharge opening 9. Arranged exteriorly in front of and beneath said discharge opening 9 is a dis-

charge trough or conduit 10 which may extend in a slight downwardly sloping inclination to and beyond either side of the tub 1 as may be desired.

- 5 Secured within said hood 8, by suitable supporting brackets 11, or any other desirable fastening means, and in a location so as to extend transversely above the discharge opening 9, is a header member 12 of 70
10 a water-screen device. One end of said header member 12 projects exteriorly through the side of said hood 8, and is provided with an interiorly threaded portion 13 into which is screwed the end of a water 75
15 supply pipe 14 leading from any suitable source of supply. Connected with the bottom wall of said header member 12 are one or more rows of downwardly directed water discharge nozzles. Preferably the said nozzles 80
20 are arranged to provide a front row of nozzles 15, obliquely inclined to the right to discharge a plurality of downwardly directed obliquely inclined water streams 16, and a rear row of nozzles 17, obliquely inclined to the left to discharge a plurality of downwardly directed oppositely obliquely inclined water streams 18. The said streams 16 and 18 are discharged between the discharge opening 9 and the beater roll 25
25 3, and form a water screen or curtain having free unobstructed interstices 19 between same. The water supplied to the header, is preferably under sufficient pressure to lend considerable force to the streams discharged 30
35 therefrom, so that they maintain their direction, and also are of sufficient strength to obstruct the passage of material therethrough not sufficiently pulped, while the interstices 19 are of sufficient size to permit 40
45 the passage therethrough of pulped material properly reduced to the fibrous condition desired.

In operating the device the tub 1 is filled with water, and the raw material to be pulped is deposited therein. The beater roll 3 is then set in motion. The rotation of the beater roll acts as a paddle upon the water in the tub, causing the same to circulate around the tub in the path defined 50 by the walls of the tub and the mid-feather 2. The circulatory flow of the water thus set up carries the raw material between the beater roll and the base plate 7 in the usual manner, thereby causing the reduction of 55 the raw material into a fibrous mass, which with the water in which it is carried produces the pulp desired. The nature of the raw material is such that almost immediately some portions thereof are reduced to 60 the necessary pulpy mass, while other portions, being more resistant, are not so reduced until, during the circulation through the tub they are carried many times into contact with the beater roll. In most constructions of beaters, as heretofore used, it 65

is necessary to permit the properly reduced portions of the raw material to continue in circulation with the rest of the mass until the whole batch is entirely reduced. This necessity entails both a loss of time and energy. With my construction of novel separating means in combination with the beater proper, however, the properly reduced or pulped portions of the raw material are, in large part, separated from the more resistant mass and discharged continuously from the hood ready for use, leaving the more resistant mass for further treatment, until it too is gradually reduced and discharged. This separation is effected as follows. During the rotation of the beater roll a certain amount of water and pulped raw material is carried around with the same, the latter being thrown outwardly by centrifugal force from the circumference of the roll. The out-flying portions of the pulp are precipitated toward the water screen and passing through the interstices 19 between the streams 16 and 18, are received in the trough 10, being thence discharged from the beater machine. 75
80 If any raw material not properly reduced, strings, rags, or other non-pulped material are thrown off by the beater roll, the same being too coarse to pass through the interstices 19 between the streams, they are 85 caught by the force of the downwardly discharged streams and carried therewith back into the tub 1, so as to be further subjected to the beating action of the beater-roll. The streams of water 16 and 18 have sufficient 90 force to provide the necessary obstacle to the passage through the discharge opening 9 of material too coarse, and consequently not sufficiently reduced or pulped to be 95 ready for discharge, and yet the greater portion of pulp which is beaten to a fine enough degree readily flies through the interstices 19 between the water streams without being engaged by the latter so as to be washed back into the tub 1. The water screen thus 100 provides a very practical separating device, which is positive and powerful enough to obstruct the outward passage of coarse un-reduced raw material, and yet because of its character, being composed of moving 105 streams of water, cannot possibly clog up or become obstructed.

While it is preferable to employ two sets of streams crossing each other obliquely, I do not wish to be understood as limiting myself entirely to such an arrangement, since it is possible to use even a single or double row of vertically descending streams effectively, when properly spaced one from the other.

It will be apparent from the above description that the discharge of properly reduced pulp will be practically continuous during the operation of the beater, and that by removing properly reduced pulp from 110 115 120 125 130

the mass of raw material circulating in the tub, the more resistant portions of the said raw material will thereupon have opportunity for more intimate contact with the beater roll, thus assuring a more rapid reduction of the same, with a consequent further saving of time and energy.

I am aware that some changes may be made in the general arrangements and combinations of the devices and parts, as well as in the details of the construction of the same, without departing from the scope of my invention as described in the foregoing specification, and as defined in the claims appended hereto. Hence, I do not limit my invention to the exact arrangements and combinations of the devices and parts as set forth in the foregoing specification, nor do I confine myself to the exact details of the construction of said parts as illustrated in the accompanying drawings.

I claim:

1. In a device of the kind described, a tub, a beater roll therein, a hood inclosing said beater roll having a discharge opening therein, a trough exteriorly arranged relative to said discharge opening, and means adjacent to said discharge opening for projecting a plurality of laterally spaced streams of water downwardly across said discharge opening to provide a water screen for the purposes described.

2. In a device of the kind described, a tub, a beater roll therein, a hood inclosing said beater roll having a discharge opening therein, a trough exteriorly arranged relative to said discharge opening, a water discharging means disposed transversely within said hood above said discharge opening, means for delivering water to said water discharging means, the latter being adapted to project a plurality of downwardly directed closely spaced streams of water across said discharge opening to form a water screen between said beater roll and said opening.

3. In a device of the kind described, a tub, a beater roll therein, a hood inclosing said beater roll having a transverse discharge opening therein, a receiving trough exteriorly disposed beneath and in front of said discharge opening, a header member secured within said hood above said discharge opening, means for delivering water under pressure to said header member, and means connected with the under side of said header member for discharging a plurality of downwardly directed closely spaced streams of water between said discharge opening and said beater roll to provide a pulp separating water screen.

4. In a device of the kind described, a tub, a beater roll therein, a hood inclosing said beater roll having a transverse discharge opening therein, a receiving trough exteriorly disposed beneath and in front of said discharge opening, a header member secured within said hood above said discharge opening, means for delivering water under pressure to said header member, a transverse row of discharge nozzles connected with said header member, the same being obliquely disposed in one direction to discharge a plurality of downwardly directed obliquely inclined streams of water between said discharge opening and said beater roll to provide a pulp separating water screen.

5. In a device of the kind described, a tub, a beater roll therein, a hood inclosing said beater roll having a transverse discharge opening therein, a receiving trough exteriorly disposed beneath and in front of said discharge opening, a header member secured within said hood above said discharge opening, means for delivering water under pressure to said header member, a transverse row of discharge nozzles connected with said header member, the same being obliquely disposed in one direction to discharge a plurality of downwardly directed obliquely inclined streams of water, a second parallel transverse row of discharge nozzles connected with the header member, the same being obliquely disposed in an opposite direction to discharge a plurality of downwardly directed oppositely inclined streams of water, said streams thus crossing each other to provide interstices through which properly reduced pulp thrown from said beater roll by centrifugal force may pass so as to be ejected through said discharge opening into said receiving trough.

6. In a device of the kind described, a tub, a beater roll therein, a hood inclosing said beater roll having a discharge opening therein, a trough exteriorly arranged relative to said discharge opening, and means adjacent to said discharge opening for discharging across the same rows of closely spaced downwardly directed streams of water in respectively oppositely inclined oblique courses to form a water screen between said beater roll and said discharge opening.

In testimony, that I claim the invention set forth above I have hereto set my hand this 31st day of January, 1918.

SIDNEY MITCHELL.
